UNITED STATES PATENT OFFICE

158,994

OPTICAL TEMPLE

Peter J. Morroni, Leominster, Mass.

Application April 10, 1950, Serial No. 9,115

Term of patent 7 years

(Cl. D57—1)

To all whom it may concern:

Be it known that Peter J. Morroni, a citizen of the United States, residing at Leominster, county of Worcester, State of Massachusetts, has invented a new, original, and ornamental Design for an Optical Temple, of which the following is a specification, reference being had to the accompanying drawing, forming part thereof.

Fig. 1 is a view in side elevation of an optical temple showing my new design;

Fig. 2 is a top plan view thereof; and

Fig. 3 is an enlarged section on line 3—3 of Fig. 1.

I claim:

The ornamental design for an optical temple, as shown.

PETER J. MORRONI.
